CLAIM

The ornamental design for a display clothes hanger, as shown and described.

DESCRIPTION

FIG. 1 is a front, side perspective view of a display clothes hanger;

FIG. 2 is a front view of the display clothes hanger;

FIG. 3 is a back view of the display clothes hanger;

FIG. 4 is a first side view of the display clothes hanger;

FIG. 5 is an opposing side view of the display clothes hanger;

FIG. 6 is a top view of the display clothes hanger; and,

FIG. 7 is a bottom view of the display clothes hanger.

The broken lines in the drawings depict portions of the display clothes hanger that form no part of the claimed design.
